UNITED STATES PATENT OFFICE.

JOHN J. CONNOR, OF YOUNGSTOWN, OHIO, ASSIGNOR TO THE YOUNGSTOWN SHEET AND TUBE COMPANY, OF YOUNGSTOWN, OHIO, A CORPORATION OF OHIO.

PIPE-MILL.

1,049,999.

Specification of Letters Patent.

Patented Jan. 7, 1913.

Application filed December 20, 1910. Serial No. 598,403.

To all whom it may concern:

Be it known that I, JOHN J. CONNOR, a citizen of the United States, residing at Youngstown, in the county of Mahoning and State of Ohio, have invented new and useful Improvements in Pipe-Mills, of which the following is a specification.

My invention relates to improvements in apparatus for drawing, sizing and cooling 10 butt-weld pipes, and its object is to arrange the drawing, sizing, and cooling devices so as to dispense with considerable labor, save valuable space in crowded plants, minimize liability to accidents and cheapen the cost of 15 production.

The accompanying drawing shows dia- 20 grammatically a plan (partly in section) of a butt-weld pipe mill with the elements arranged according to my invention, it being understood that I have not undertaken to 25 show the details of the various parts because they are all well-known, but that I have merely indicated conventionally the presence of certain elements at certain places.

25 On the drawing referred to, 1 designates the skelp-heating furnace, in which the skelp 2 lie and are heated in the usual manner.

30 3 is a pivoted draw-bench arranged to oscillate on the pivot 4 so that its front end may be placed opposite the end of any one of the several skelp 2 in the furnace 1 in a well known manner.

35 5 is a pair of tongs or other pipe drawing device adapted to be connected to the nose or front end of the skelp and to the draw-chain 6 shown in dotted lines, whereby the skelp may be drawn through the welding die 7 seated on the front end of the 40 draw-bench 3.

45 8 designates the sizing rolls (only the top one being shown), which are situated directly back of the draw-bench 3 and approximately in line therewith so that, after 50 the tongs have been disconnected from the draw-chain 6, the latter will carry the pipe with the tongs attached rearwardly into the pass of the sizing rolls 8. From the rolls 8 the pipe and tongs pass into the trough 9 at the rear of the said rolls and in line therewith.

55 The pipes pass automatically or by aid of an attendant from the trough upon the cooling rack of well-known construction. I have shown enough to indicate that I have

in mind that type of cooling rack which has the sprocket chains 10 running thereon to carry the pipe slowly thereover in the usual manner. While the pipes are cooling on the rack or while they are in the 60 trough, the cooling rack attendant takes off the tongs.

The drawing apparatus may be the old well known apparatus which employs boys, called hook-runners, to connect the tongs to 65 the chain by means of hooks, which are removed by the hook-runners after the skelp has left the welding die; but drawing apparatus of a different construction may be employed.

70 Heretofore, the pipe with the tongs attached has been, after the tongs have been disconnected from the chain, guided laterally from the draw-bench onto a number of inclined skids, over which the pipes were 75 guided into a sizing-trough at the outer end of the skids. Before the pipe was put into the trough, an attendant, called the taker-off, who was stationed between the bench and the trough and at the rear of the 80 skids removed the tongs from the pipe. After the pipe had reached the sizing trough, it was passed through the sizing rolls situated immediately to the rear of the trough and directly in line therewith. 85 From the sizing rolls the pipe passed along another trough and through a second set of rolls with axes inclined to each other, these rolls being called the cross-rolls. After the pipe emerged from the cross-rolls, it was 90 transferred to the cooling-rack.

95 With my improved arrangement of apparatus, I dispense with the devices required to guide the tongs and connected pipe to the taker-off and the skids; I dispense with the taker-off, the skids, the sizing trough, attendants therefor, and the cross-rolls. I save a large amount of valuable space which can be utilized for other purposes, and I save the wear which the pipe 100 produces on the sizing trough and which the cross-rolls cause to the trough between the sizing and cross-rolls. I arrange the furnace, the draw-bench, the sizing-rolls, and the feeding-in end of the cooling rack in a straight line, except that the draw-bench, when drawing skelp at either side of the one shown on the drawing as about to be drawn, will make a small angle with the axes of the 105 sizing rolls 8. This angle is so small that 110

it may be said that the sizing rolls 8 are approximately in line with the draw-bench. Heretofore it has been considered necessary to deliver welded tubes to the sizing rolls 5 exactly at right angles to their axes. For this reason it has been regarded as necessary to transfer the pipe from the swinging draw-bench to the sizing trough which was arranged exactly at a right angle to the axes 10 of the sizing rolls. By arranging the sizing rolls directly at the rear of the draw-bench, the red hot metal is exposed for a much shorter period to the oxidizing action of the air in its passage from the furnace to the 15 cooling rack. Furthermore, the draw-chain acts as a conveyer of the pipe to the sizing rolls, thereby dispensing with the attendants and equipment heretofore required to transfer the pipe from the draw-bench to the sizing trough and the sizing rolls. I dispense with the services of all attendants, except 20 the welders, the hook-runners, tongs-carrier and the cooling rack attendants.

What my improvement saves in apparatus, attendants, and space may be seen by reference to Simpson's Patent, No. 452,114 which shows a movable draw-bench, skids, a sizing trough, sizing rolls, and cross-rolls, tongs being used in place of tongs and the 25 cooling-rack being omitted.

Claim—

1. In a pipe mill, the combination with a 30 welding die of sizing rolls, and an intermediate draw-bench having a draw-chain thereon, means for detachably connecting the pipe and the draw-chain, whereby the said draw-chain may act as a conveyer of the welded pipe to the sizing rolls after the tube

and the said connecting means have been disconnected.

2. In a pipe-mill, a skelp-heating furnace, sizing rolls, and a draw-bench arranged lengthwise between the furnace and the sizing rolls, provided with a draw-chain, and pivoted at the end nearest the sizing rolls, 45 the pivotal point of the draw-bench being substantially in the vertical plane including the axis of the pass of the sizing rolls.

3. In a pipe-mill, the combination of a skelp-heating furnace, of sizing rolls, and a draw-bench arranged lengthwise between the furnace and the sizing rolls and having a draw-chain having travel toward and substantially in line with the sizing rolls, welding tongs adapted to engage the skelp, and means for detachably connecting the tongs and the draw-chain whereby the draw-chain may act as a conveyer of the welded pipe and the attached tongs toward the sizing rolls after the said tongs and the draw-chain have been disconnected.

4. In a pipe-mill, a skelp-heating furnace, sizing rolls, and a draw-bench arranged lengthwise between the furnace and the sizing rolls, provided with a draw-chain and pivoted at the end farthest from the furnace, which draw-chain is, when the draw-bench is in its central position, substantially 65 in the vertical plane including the axis of the pass of the sizing rolls.

Signed at Youngstown, Ohio, this 15th day of December, A. D. 1910.

JOHN J. CONNOR.
